GRINDING MACHINE STEADY REST

Herbert A. Silven, Worcester, Mass., assignor to
 Norton Company, Worcester, Mass., a corpora-
 tion of Massachusetts

Application November 19, 1941, Serial No. 419,763

6 Claims. (Cl. 51—238)

The invention relates to grinding machines, and more particularly to a steadyrest for supporting and steadyng a work piece during a grinding operation.

One object of the invention is to provide a simple and thoroughly practical steadyrest for a cylindrical type grinding machine. Another object of the invention is to provide a steadyrest which may be rapidly and readily moved to and from an operative position. Another object of the invention is to provide a two-bearing shoe type steadyrest which is pivotally mounted and arranged so that it may be swung to and from an operative position to facilitate a longitudinal indexing movement of the steadyrest. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a left-hand end elevation, partly in section, of the improved steadyrest in position on the grinding machine table;

Fig. 2 is a fragmentary plan view of the steadyrest as shown in Fig. 1;

Fig. 3 is a front elevation of the improved steadyrest;

Fig. 4 is a rear elevation of the improved steadyrest, that is, a view taken looking at the steadyrest from the position of the grinding wheel; and

Fig. 5 is a fragmentary plan view of the toggle actuated clamping mechanism.

A steadyrest has been illustrated in the drawings as mounted on a grinding machine table 10 which is arranged for a longitudinally reciprocatory movement relative to the base of the machine, as is old and well known in the prior art of record. The improved steadyrest is particularly adapted for use on a crankshaft grinding machine such as, for example, that shown in the prior U. S. Patent to Herbert A. Silven, No. 2,151,666 dated March 21, 1939. In a machine of this type, the steadyrest is ordinarily located on the machine table and is arranged so that it may be positioned opposite the operative face of a rotatable, transversely movable grinding wheel 11 so that the steadyrest shoes will support a pin 12 of a crankshaft to be ground. The steadyrest

together with the steadyrest shoes is arranged so that it may be readily moved to and from an operative position so that after one pin on the crankshaft has been ground, the steadyrest may be readily moved longitudinally relative to the table to position it in supporting engagement with another crankpin after the crankpin has been positioned in operative relation with the grinding wheel 11.

10. A steadyrest base 15 is provided which may be readily clamped in position on the work supporting table 10. The under surface of the steadyrest is provided with supporting bearing surfaces 16, 17 and 18 which mate with correspondingly shaped surfaces on the work supporting table 11. A clamping member 19 is pivotally supported by a stud 20 on the steadyrest base 15 and is arranged to be moved into or out of engagement with the clamping lug 21 fixedly supported on the upper surface of the table 10. A slidably mounted rod 22 on the steadyrest base is provided with nuts 23 on its right-hand end (Fig. 1) which engage the clamping member 19. A manually operable lever 24 is provided for actuating a toggle lever connection 25 between the lever 24 and the rod 22 whereby the clamping member 19 may be readily moved into a clamping position to lock the steadyrest frame 15 in an operative position on the table 10, or may be readily released therefrom when desired.

The steadyrest base 15 is provided with a pair of spaced, parallel, upwardly extending side plates which serve as a support for a pivotally mounted steadyrest frame 28. A pivot stud 29, which is fixedly mounted to the plates 26 and 27 and passes through an aperture in the steadyrest frame 28, serves to pivotally support the frame 28 so that it may be readily swung to and from an operative position as desired. The steadyrest frame 28 serves as a support for a pair of work steadyng shoes 30 and 31. The steadyrest shoe 30 is arranged to engage the crankpin 12 being ground at a point diametrically opposite the line of contact between the grinding wheel 11 and the work piece 12. The steadyrest shoe 31 is arranged to engage the work piece at a point below the work axis and at a point adjacent to the line of contact between the grinding wheel 11 and the work piece 12.

50. The work steadyng shoe 30 is fixedly mounted on the forward end of a slide 32 which is slidably supported within the frame 28. A manually operable screw 33 engaging or meshing with a nut 34 which is fixedly mounted within the frame 28 is connected at its inner end to move the slide 32.

A manually operable adjusting knob 35 is mounted on the outer end of the screw 33 and is held in a clamped adjusted position thereon by means of a clamping and stop member 36. It will be readily apparent from the foregoing disclosure that a rotary motion of the knob 35 will be transmitted through the screw 32 to cause a transverse adjustment of the work steadyng shoe 30.

The steadyrest shoe 31 is mounted on the right-hand end of a pivotally mounted lever 37 (Fig. 1) which is pivotally supported by a stud 38 on the frame 28. In order to adjust the position of the shoe 31, the lever or arm 37 is provided with a roller 39 which is engaged by a slidably mounted wedge 40 which is slidably supported within the frame 28. An adjusting screw 41 is screw threaded into a nut 42 fixedly supported within the frame 28. The right-hand end of the screw member 41 is rotatably supported within a bearing 43, and a head 44 formed on the right-hand end of the screw member 41 engages and is operatively connected to move the wedge member 40 relative to the frame 28 so as to raise and lower the steadyrest shoe 31 by swinging the arm 37 about its supporting pivot 38. An actuating knob 45 is mounted on the left-hand end of the screw member 41 and is arranged to be clamped in adjusted position on the screw 41 by means of a combined clamping and stop member 46.

The clamping and stop members 36 and 46 are arranged to engage stop pins or studs 47 and 48, respectively, which are fixed on the left-hand end face of the frame 28 and which serve to limit the rotary movement of the screws 33 and 41, respectively, when turned to cause an approaching movement of the shoes 30 and 31, respectively. It will be readily apparent from the foregoing disclosure that the knobs 35 and 45, respectively, may be adjusted to any position on the screws 33 and 41, respectively, to set up the rest so that when the clamp and stop members 36 are rotated to cause an approaching movement of the steadyrest shoes 30 and 31 toward the work axis, the clamping and stop members 36 will rotate so that they engage the stop studs 47 and 48, respectively, to limit the rotary adjustment of the screws and thus to stop the forward progress of the steadyrest shoes 30 and 31, respectively.

A pivotally mounted lever 50 is supported by a pivot stud 51 which is fixed relative to the steadyrest base 15. The upper end of the lever 50 is provided with a notch 52 which engages the lower right-hand corner 53 of the steadyrest frame 28 and serves normally to hold the steadyrest frame in an operative position. A tension spring 54 located between the side plates 26 and 27 is connected at one end to a stud 55 which is fixedly supported on the steadyrest frame 28. The other end of the spring 54 is connected to a stud 56 fixedly supported by the upper end of the clamping block 19. The spring 45 normally tends to hold the steadyrest frame 28 in an operative position. The tension of the spring may be adjusted by means of the stud 55 which is screw threaded and is held in a clamped adjusted position by a pair of nuts 57 and 58 which are arranged on opposite sides of an end plate 59 which is fixedly supported on the steadyrest frame 28. The pivot stud 29 for the frame 28 is arranged so that the force of gravity tends to rock the steadyrest frame 28 to an inoperative position. The tension of the spring 54 is adjusted to partially counterbalance the overhanging weight of the steadyrest 28.

The arm 50 is normally held in the position shown in Fig. 1 by means of a tension spring 60 which is connected between a stud 61 fixedly supported on the lever 50 and a stud 62 which is fixedly mounted on the clamping block 19. When it is desired to swing the steadyrest frame 28 together with the work steadyng shoes 30 and 31 to an inoperative position, the arm 50 is swung in a clockwise direction and the steadyrest frame 28 swung in a clockwise direction into position 28a so that the lower surface of the frame 28 engages an adjustable stop screw 63 which is adjustably supported on the steadyrest base 15. When the steadyrest is in position 28a, the work steadyng shoes 30 and 31 are in broken line positions 30a and 31a (Fig. 1). To facilitate swinging the arm 50 from the operator's station adjacent to the front of the machine, a rod 65 is slidably supported in bearings 66 and 67 formed on the under side of the steadyrest frame 28. The right-hand end of the rod 65 (Fig. 1) engages the lever 50. A manually operable knob or handle 68 is fixedly clamped to the left-hand end of the rod 65 (Fig. 1). It will be readily apparent from the foregoing disclosure that when the knob or handle 68 is moved toward the right (Fig. 1), that is, away from the operator when standing in front of the machine, the rod 65 will move also in a direction toward the right (Fig. 1) to rock the lever 50 in a clockwise direction to release the steadyrest frame 28 so that it may readily swing under the influence of gravity to an inoperative position, as indicated in broken lines into position 28a (Fig. 1).

When it is desired to again shift the steadyrest frame 28 and shoes 30 and 31 into an operative position with relation to the work piece 12, the frame 28 may be readily swung in a counterclockwise direction into the position illustrated in Fig. 1, in which position the arm 50 is swung into the latched supporting position by the tension of the spring 60.

The operation of this improved steadyrest will be readily apparent from the foregoing disclosure. Assuming the rest to have been previously clamped in adjusted position on the table 10, the steadyrest frame 28 is manually swung in a counterclockwise direction into the position illustrated in Fig. 1, after which the manually adjustable knobs 35 and 45 may be rotated independently to move the steadyrest shoes 30 and 31 into supporting and steadyng engagement with the work piece 12 during the grinding operation. As the grinding operation proceeds, the steadyrest shoes 30 and 31 may be maintained in the desired supporting relationship with the work piece 12 as it is reduced in size by grinding, by manual manipulation of the knobs 35 and 45, respectively. After a grinding operation has been completed, the knobs 35 and 45 are rotated in the reverse direction to move the steadyrest shoes 30 and 31, respectively, away from the work surface by an amount slightly greater than the amount of stock removed during the grinding operation, after which the knob or handle 68 is moved toward the right (Fig. 1) to rock the arm 50 in a clockwise direction so that the steadyrest frame may swing under the influence of gravity to position 28a, that is, to an inoperative position with the shoes 30 and 31 in broken line positions 30a and 31a, separated a considerable distance from the work piece 12 so that the steadyrest base 15 may be readily adjusted or indexed longitudinally along the table 10 after the table has been indexed to

position the next portion of the work piece 12 for a grinding operation.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine, a steadyrest comprising a steadyrest base which may be readily clamped on a grinding machine table, a pair of spaced, parallel, upwardly extending plates thereon, a pivotally mounted steadyrest frame between said plates, a stud supported by said plates which serves as a pivotal support for said frame, a work steadyng shoe adjustably supported on said frame, means to adjust said shoe relative to said frame, a latch normally to maintain said frame in an operative position with said shoe in engagement with a work piece, and means to trip said latch so that the steadyrest frame and shoes may swing under the influence of gravity to an inoperative position.

2. In a grinding machine, a steadyrest comprising a steadyrest base which may be readily clamped on a grinding machine table, a pair of spaced, parallel, upwardly extending plates thereon, a pivotally mounted steadyrest frame between said plates, said plates serving as guides for said frame, a stud supported by said plate which serves as a pivotal support for said frame, a pair of work steadyng shoes adjustably supported on said frame, means independently to adjust said shoes relative to said frame, a latch normally to maintain said frame in an operative position with said shoes in engagement with a work piece, and manually operable means to trip said latch so that the steadyrest frame and shoes may swing under the influence of gravity to an inoperative position.

3. In a grinding machine, a steadyrest comprising a steadyrest frame, a pair of spaced, parallel, upwardly extending plates thereon, a pivotally mounted steadyrest frame between said plates, said plates serving as guides for said frame, a pivotal support for said frame on said plates, a pair of work steadyng shoes adjustably supported thereon, means to adjust said shoes relative to said frame, said frame being pivotally supported so that it may be swung to and from an operative position, said pivotal support being arranged so that the force of gravity normally tends to hold the frame in an inoperative position, a tension spring partially to overcome the force of gravity,

5 a latch to hold said frame in an operative position, a spring normally tending to hold said latch in an operative position, and manually operable means to trip said latch to facilitate movement of the frame to an inoperative position.

4. A grinding machine steadyrest comprising a base which is detachably mounted on a grinding machine table, a steadyrest frame pivotally supported on said base and arranged so that the influence of gravity normally tends to swing said frame to an inoperative position, a horizontally adjustable work steadyng shoe on said frame, means to adjust said shoe relative to said frame, a pivotally mounted shoe on said frame which is arranged to engage the work at a point below the work axis and adjacent to the line of contact between the grinding wheel and the work, means including a slidably adjustable wedge on said frame to adjust the latter shoe relative to said frame, a latch pivotally mounted on said base normally to maintain said frame and shoes in operative position, and manually operable means to trip said latch to facilitate movement of said frame and shoes to an inoperative position.

5. In a grinding machine steadyrest comprising a steadyrest base detachably supported on a grinding machine table, a pair of spaced, parallel, upwardly extending plates on said base, a pivotally mounted steadyrest frame supported thereon, a stud supported by said plates which serves as a pivotal support for said frame, a pair of work steadyng shoes adjustably supported on said frame, means independently to adjust said shoes relative to said frame, a latch pivotally mounted on said base, a notch on said latch to engage a portion of said frame normally to maintain said frame in an operative position with the shoes in engagement with a work piece, a tension spring normally to maintain said latch in an operative position, and manually operable means slidably supported on said frame to trip said latch so that the frame and shoes may swing under the influence of gravity to an inoperative position.

6. In a grinding machine steadyrest comprising a steadyrest base detachably mounted on a grinding machine table, a pivotally mounted steadyrest frame supported on said base, a pair of steadyrest shoes adjustably supported on said frame, means independently to adjust said shoes relative to said frame, a latch pivotally mounted on said base to maintain said frame in an operative position, a tension spring normally to maintain said latch in an operative position, a tension spring to partially counterbalance the weight of said pivotally mounted frame, and a manually operable means slidably mounted on said frame to trip said latch so that the frame and shoes swing under the force of gravity to an inoperative position.

HERBERT A. SILVEN.
